CLAIM

The ornamental design for dosage packaging for washing agents, as shown and described.

DESCRIPTION

FIG. 1 is a top, front perspective view of a dosage packaging for washing agents according to a first embodiment of our new design;

FIG. 2 is a top plan view thereof;

FIG. 3 is a bottom plan view thereof;

FIG. 4 is a front view thereof;

FIG. 5 is a back view thereof;

FIG. 6 is a right-side view thereof; and,

FIG. 7 is a left-side view thereof.

FIG. 8 is a top, front perspective view of a dosage packaging for washing agents according to a second embodiment of our new design;

FIG. 9 is a top plan view thereof;

FIG. 10 is a bottom plan view thereof;

FIG. 11 is a front view thereof;

FIG. 12 is a back view thereof;

FIG. 13 is a right-side view thereof; and,

FIG. 14 is a left-side view thereof.

The broken lines are shown for the purpose of illustrating parts of the article that form no part of the claimed design.

1 Claim, 10 Drawing Sheets
